DESIGN FOR A GUN RECOIL PAD OR SIMILAR ARTICLE

Alma K. Anderson, Chicago, Ill., assignor to Red Head Brand Company, Chicago, Ill., a corporation of Illinois

Application April 19, 1937, Serial No. 68,865

Term of patent 14 years

To all whom it may concern:

Be it known that I, Alma K. Anderson, a citizen of the United States and residing in the city of Chicago, in the county of Cook and State of Illinois, have invented a new, original, and ornamental Design for a Gun Recoil Pad or Similar Article, of which the following is the specification, reference being had to the accompanying drawing, forming a part thereof.

In the drawing:

Fig. 1 is a side elevational view of my novel gun recoil pad, the other side being the same.

Fig. 2 is a rear elevational view thereof showing the surface of the pad adapted to be placed against the shoulder.

I claim:

The ornamental design for a gun recoil pad or similar article, substantially as shown and described.

ALMA K. ANDERSON.
